Inventor.

Solomon C. Spring

United States Patent Office.

SOLOMON C. SPRING, OF BRISTOL, CONNECTICUT.

Design No. 4,290, dated August 9, 1870.

DESIGN FOR A CLOCK-CASE FRONT.

The Schedule referred to in these Letters Patent and making part of the same

I, SOLOMON C. SPRING, of Bristol, in the county of Hartford and State of Connecticut, have invented and produced a new and original Design for a Clock-case Front, of which the following is a specification.

In the accompanying drawings—

A designates the base, the upper corners of which are rounded.

The frame of the case is composed of three moldings, as in the patent granted to myself June 8, 1869.

B is the outer bead or molding on both the sides and top of the case.

C is a gilt molding, composed of a plane surface and a groove; and

D, a smaller bead or rounding molding.

Inside of these three moldings, which compose the frame, is the sash E.

The top of the case is divided into two parts, placed at an angle of about eighty-two degrees to the sides of the case, and meeting each other at the center.

The top of the sash E is of a corresponding shape.

I claim as my invention—

The design for a clock-case front, as described and shown in the accompanying drawings.

SOLOMON C. SPRING.
